UNITED STATES PATENT OFFICE.

WILLIAM ALLEN TETLOW, OF SALEM, OHIO.

BUTTON.

No. 906,335.

Specification of Letters Patent.

Patented Dec. 8, 1908.

Application filed April 20, 1908. Serial No. 428,044.

To all whom it may concern:

Be it known that I, WILLIAM ALLEN TETLOW, a citizen of the United States of America, residing at Salem, in the county of Columbiana and State of Ohio, have invented certain new and useful Improvements in Buttons, of which the following is a specification, reference being had therein to the accompanying drawings.

10 This invention relates to buttons of that type commonly styled "bachelor buttons."

The objects of my invention are, first, to provide a simple and inexpensive button; second, to obviate the necessity of sewing a button to a piece of fabric; and third, to provide positive and reliable means for securing a button to a piece of fabric.

I attained the above objects by a structure that will be presently described and then 20 specifically pointed out in the appended claim.

Referring to the drawings forming a part of this specification, Figure 1 is a vertical sectional view partly in elevation of my button. 25 Fig. 2 is a plan of the disk forming the back of the button. Fig. 3 is an elevation of the same. Fig. 4 is a plan of a cap holding disk. Fig. 5 is a vertical sectional view of the same. Fig. 6 is a plan of a cap constituting the 30 front of a button, and Fig. 7 is a vertical sectional view of the same.

In the accompanying drawings, 1 designates an inner attaching disk provided with a plurality of pins 2 extending at right angles 35 with respect thereto. These pins are adapted to extend through the piece of fabric 3 to which the button is to be secured.

The reference character 4 designates an intermediate circular cap coupling member 40 having openings 5 formed therein and through these latter are adapted to extend the pins 2 when the button is secured to a gar-

ment. The member 4 is adapted to be secured to a cap 7 for coupling the latter to the attaching disk 1, the latter being positioned against one inner face of the fabric while the member 4 is positioned against the other face of the fabric and inclosed by the cap 7 which has projecting from its inner face an interiorly threaded collar 8 of less 45 diameter than the cap 7. The collar 8 is adapted to receive the member 4 which has peripheral threads 6 for engagement with the threads of the collar.

When the elements of the button are set up 55 with respect to a garment or piece of fabric, the pins 2 extend through the openings 5 of the member 4 and are clenched upon the said members through the medium of the inner face of the cap 7, by such procedure the 60 button is secured in position.

The disc 1, member 4 and cap 7 can be made of metal or any durable composition, while the pins 2 are formed of a suitable metallic material which will readily bend.

Having now described my invention what I claim as new, is:—

A button of the type described comprising an inner attaching disk provided with a plurality of pins, a peripheral toothed circular coupling member formed with a plurality of openings through which the pins are adapted to extend, and a cap provided with interior threads and adapted to receive and engage the threads of said member whereby said cap and member are connected together and the pins clenched upon said member for connecting the disk thereto.

In testimony whereof I affix my signature in the presence of two witnesses.

WILLIAM ALLEN TETLOW.
